UNITED STATES PATENT OFFICE.

VICTOR H. JENNINGS, OF WORCESTER, MASSACHUSETTS, ASSIGNOR TO MILLS WOVEN CARTRIDGE BELT COMPANY, OF WORCESTER, MASSACHUSETTS, A CORPORATION OF MASSACHUSETTS.

WOVEN FABRIC.

No. 924,788.

Specification of Letters Patent.

Patented June 15, 1909.

Application filed March 23, 1908. Serial No. 422,823.

To all whom it may concern:

Be it known that I, VICTOR H. JENNINGS, a subject of Great Britain, residing at Worcester, in the county of Worcester, State of Massachusetts, have invented a certain new and useful Improvement in Woven Fabrics, of which the following is a specification, reference being had therein to the accompanying drawings.

10 The invention is an improvement in fabrics or webs of that kind which are woven of one width in one portion of the length thereof, and of a different width in a succeeding portion, examples of such fabrics or webs 15 being shown and described in United States Letters Patent No. 859,067, granted under date of July 2, 1907.

The main object of the invention is to add to the thickness of the broad portion of a 20 fabric or web of the said kind, or give increased body, and also to give added strength.

The invention consists, accordingly, in a fabric or webbing having portions of different 25 widths as aforesaid, and provided with a longitudinal thickening or reinforce woven integral therewith, as will be explained with reference to the drawings.

The invention is of particular value in the 30 case of a web or fabric in which the warp-threads all extend continuously throughout the length, and the narrow and broad portions both contain the same number of threads. In such case, the broad web-portion 35 ordinarily has less thickness and substance than the narrow web-portion.

Figure 1 of the latter shows a view of one 40 face of a short piece of fabric of two widths. Fig. 2 is a view of the other face of such fabric and shows a longitudinal thickening or reinforce such as has just been referred to. Fig. 3 is a diagram illustrative of one manner of carrying the invention into effect, and shows the different portions of the broad 45 part of the fabric in the relative positions which they occupy in the loom in being woven. Fig. 4 is a diagram showing the fabric-section of Fig. 3 opened out flat, as in its final state subsequent to removal from the 50 loom. Fig. 5 is a diagram similar to Fig. 3, but showing a supplemental layer or ply that is bound to the main web at additional points in the width thereof. Fig. 6 is a diagram like Fig. 4, but showing the fabric of Fig. 5

opened out flat. Fig. 7 is a diagram similar 55 in character to Figs. 3 and 5 but showing an embodiment of the invention in which the margins of the band of thickening are interwoven solidly with the adjacent portions of the web or fabric. Fig. 8 shows the fabric 60 of Fig. 7, opened out flat.

In Figs. 1 and 2 the narrow portion or width of the web or fabric is marked A; and the broad portion is marked B. As in the Letters Patent aforesaid, the same warp-threads are continuous throughout the web or fabric, and the same number of threads is contained in both widths. In the narrow portion or width A, the said warp-threads are interwoven with the weft or filling in approved manner into a plurality of layers or plies, which are joined or closed together. In the broad portion certain of the warp-threads are woven into distinct wings or plies, A', A', Fig. 1, which are unconnected 75 with each other but respectively connected or joined in the weaving with the remaining portion of the web or fabric at opposite sides of the middle of the width of the latter. These wings or plies when spread out flat 80 give the increased width to the portion B. Figs. 1 and 2 show the demarcation between the narrow and broad portions, and illustrate the taper where the free edges of the webs or plies are spread obliquely across the face of 85 the web or fabric. The addition to the thickness of the broad portion of the web or fabric is shown at C, Fig. 2, in the form of a band of the same width as the narrow portion A of the web or fabric, extending along the 90 middle of the width of the broad portion B in continuation of the said narrow portion.

The character and weave of the web or fabric A, B, and of the additional layer or thickness at C, and the manner of producing 95 and combining the latter with the broad portion B in the weaving, may be varied in different respects. Fig. 4 is a diagram of an instance in which it is practically a distinct and separate cloth or web, connected with 100 the portion B only along the middle line at a. Fig. 3 is a diagram of the mode of weaving, according to which the fabric is produced in the loom in four layers or plies, the two uppermost constituting the wings which 105 are designed to furnish the increase of the width of the broad web-portion B over narrow web-portion A, the third layer or ply

- constituting the middle portion of the width of broad web-portion B, and the fourth layer or ply constituting the additional layer or thickness. In weaving the web or fabric of Figs. 3 and 4, the first pick of weft or filling is interwoven from left to right with the warp-threads of the uppermost layer or ply; the second pick is interwoven from right to left in the same ply, completing the latter. The third pick interweaves from left to right with the warp-threads of the left-hand half of the width of the third layer or ply, and then passes into the fourth ply and interweaves with the warp-threads of the right-hand half of the latter. The fourth pick interweaves from right to left with the warp-threads of the fourth ply, entirely across the width of the said ply. The fifth pick interweaves from left to right with the warp-threads of the left-hand half of the fourth ply, completing the latter, and then passing into the third ply interweaves with the right-hand half of the warp-threads thereof. The sixth pick interweaves from right to left with the warp-threads of the second ply, and the seventh pick interweaves from left to right therewith, completing the said second ply. Finally, the eighth pick interweaves with the warp-threads of the third ply from right to left, completing the said ply and finishing the round. The diagram of Fig. 4 represents the first and second plies spread apart and flattened out. The passage of pick 3 of the weft or filling from the third ply to the fourth, and of pick 5 from the fourth ply to the third, unites the said fourth ply to the main portion of the web or fabric at the point *a*, which is located at the middle of the width of the web or fabric. Consequently, the fourth ply, although presenting the appearance of a separate strap lying against the main web or fabric, in continuation of the narrow web-portion A, is integrally joined to the said main web-portion along the middle line of the broad portion of the fabric or web, and cannot be detached therefrom except by cutting the connecting threads.
- Figs. 5 and 6 show diagrams similar to those of Figs. 3 and 4, but according to which the fourth ply (constituting the supplemental layer) is bound to the third ply at additional points in the width, namely, at *b* and *c* as well as at point *a*. Thus, the fourth pick of weft or filling is, in Figs. 5 and 6, caught by the second warp-thread at the right-hand side of the third ply, and also is caught by the second warp-thread at the left-hand side of such ply. The result is that the supplemental layer is also tied to the main web along lines close to the opposite edges of such layer, so that the margins of the latter, while formed as finished selvages, are distinct and not bound closely to the surface of the main web.
- In the diagrams of Figs. 7 and 8 the weave is different in certain respects from that of Figs. 3 and 4. The first and second picks of weft or filling are interwoven in the first ply as in Figs. 3 and 4, completing such ply. The third pick is interwoven from left to right with the warp-threads of the fourth or reinforcing ply, being caught at the middle point *d* by one of the warp-threads of the third ply, and the fourth pick interweaves from right to left with the warp-threads of the third ply. The fifth pick interweaves from left to right with the warp-threads of the fourth or reinforcing ply, completing such ply, the said pick being caught at the point *e* around the second warp-thread at the left of the third ply, and also at the point *f* around the second warp-thread at the right. The sixth and seventh picks are interwoven with the warp-threads of the second ply as in Figs. 3 and 4, completing such ply, and the eighth pick is interwoven from right to left with the warp-threads of the third ply, completing such ply and finishing the round. The result produced by the weave shown in Figs. 7 and 8 is that the fourth ply is interwoven at its side margins with the remainder of the web, as well as at the middle, so that the said margins are rounded and bound solidly to the adjoining web-portions.
- Fabrics embodying the invention are of particular value for use in the manufacture of belts and the like, and of shoulder-straps, as, for instance, those which form parts of suspenders, notably those used as a part of military equipments.
- What is claimed as the invention is:—
1. An inelastic fabric or web woven with narrow and broad portions and with a longitudinal inextensible thickening or reinforcement integral with the broad portion.
  2. An inelastic fabric or web woven with narrow and broad portions and with an integral inextensible supplemental or thickening layer extending longitudinally of the broad portion.
  3. An inelastic fabric or web woven in narrow and broad portions and with an inextensible thickening or reinforcement integral with the broad portion and in continuation of the narrow portion.
  4. An inelastic fabric or web woven in narrow and broad portions containing the same number of warp-threads, and with a portion of such warp-threads formed into a longitudinal inextensible thickening extending lengthwise of the broad portion.
  5. A fabric or web having a narrow portion in which the warp-threads are interwoven into a plurality of layers or plies bound or closed together, and a broad portion in which certain of such warp-threads are interwoven into one or more lateral web-portions affording the increased width, and having certain others of such warp-threads formed into a supplemental layer or thick-

ening which extends longitudinally of the broad portion.

6. A fabric or web woven in narrow and broad portions containing the same number of warp-threads, the latter being continuous throughout both of such portions, and the said broad portion thickened or reinforced.

In testimony whereof I affix my signature in presence of two witnesses.

VICTOR H. JENNINGS.
